187,978

BANK TELLER'S MOBILE BOOTH

James Grewe, Somerville, Ohio, assignor, by mesne assignments, to Diebold, Incorporated, Canton, Ohio, a corporation of Ohio

Filed Oct. 2, 1958, Ser. No. 52,846

Term of patent 14 years

(Cl. D13—1)

Fig. 1.

Des. 187,978

PAGE 2

I claim:

The ornamental design for a bank teller's mobile booth, as shown.
